(No Model.)

G. D. STONESTREET.

ORE CONCENTRATOR.

No. 365,279.

Patented June 21, 1887.

UNITED STATES PATENT OFFICE.

GEORGE D. STONESTREET, OF BIRMINGHAM, ALABAMA, ASSIGNOR, BY DIRECT AND MESNE ASSIGNMENTS, TO REGINALD STONESTREET AND THOMAS E. ENLOE, BOTH OF NASHVILLE, AND WARREN SMITH, OF SMITH'S FORK, TENNESSEE.

ORE-CONCENTRATOR.

SPECIFICATION forming part of Letters Patent No. 365,279, dated June 21, 1887.

Application filed January 16, 1886. Serial No. 188,759. (No model.)

To all whom it may concern:

Be it known that I, GEORGE DAVID STONESTREET, a subject of the Queen of Great Britain, residing at Birmingham, in the county of Jefferson and State of Alabama, have invented certain new and useful Improvements in Ore-Concentrators; and I do hereby declare the following to be a full, clear, and exact description of the invention, such as will enable others skilled 10 in the art to which it appertains to make and use the same.

My invention relates to an improvement in ore-concentrators.

The object is to provide a concentrator which 15 will effectually agitate the material fed into engagement therewith, and which shall be capable of the nicest adjustment for preventing waste in the treatment of material of different specific gravities.

20 A further object is to provide a simple, inexpensive, and effective concentrator suitable for all grades of work.

With these ends in view my invention consists in certain features of construction, as will 25 be hereinafter described, and pointed out in the claim.

In the accompanying drawings, Figure 1 is 30 a top plan view of the concentrator with the distributor removed. Fig. 2 is a vertical central section of same with the distributor in position, and Fig. 3 is a detached end view of one of the knife-holding arms with knife in position.

A represents a suitable supporting-frame, the bottom of which is provided with an annular 35 groove adapted to receive and form a seat for the annular groove or recess C, formed at the periphery of the bottom of the pan B. The pan B is preferably provided with outwardly-flaring sides, and its bottom gradually rises 40 from its periphery toward the center, where it is provided with a funnel-shaped outlet, M. An upright shaft, S, is located centrally within the funnel-shaped outlet M, its lower end being seated in a suitable bearing on the step N. The 45 shaft S extends upwardly above the top of the pan B, and has secured rigidly thereto the knife-supporting arms D and the distributor E. The knife-supporting arms D are preferably eight

in number and radiate at equal distances apart from the shaft S at points a short distance above 50 the highest portion of the bottom of the pan.

To the arms D are secured the vertical knives K, as shown in detail, Fig. 3, the said figure representing an enlarged end view of one of the arms D with the knife in position for use. 55

The arm may be constructed in skeleton form, with its upper and lower edges projecting laterally therefrom, or it may be provided at proper intervals with laterally-extending lugs or ears. 60

Through corresponding perforations in the edges of the arm or in the lugs or ears the stems k of the knives K extend with a loose fit, and by means of a draw-bolt, k', one end of which embraces the stem k and the opposite end of 65 which extends through the body of the arm, and a nut, k'', on the threaded end of the bolt, the knife K may be locked to the arm in the desired vertical or angular adjustment.

The knives are attached to the arms in such 70 positions as to form, when considered collectively, a spiral. (Designated by the dotted line 2, Fig. 1.)

The distributor E consists, essentially, of an inverted funnel extending from the mouth of 75 the feed-hopper H to the ends of the arms D, over or slightly beyond the groove or recess C in the bottom of the pan.

The distributor is conveniently secured to the ends of the arms and to the shaft at its 80 apex, and is thereby caused to rotate simultaneously with the shaft.

The neck of the feed-hopper H is provided with openings R, through which the material fed into the mouth of the hopper passes out onto 85 the distributor, and is by the rotary motion thereof evenly distributed around the side of the pan B, where it falls into contact, to a greater or less extent, with the mercury, which is supposed to fill the recess or groove C, and the lighter portions of the crushed ore and waste, together with such portions of the ore as have not come into contact with the mercury, tend to pass thence with the waste toward the outlet M. The general movement of 90 the mass not held by the mercury toward the 95

outlet M is caused by the strong current due to the weight of the material, which is continually fed to the machine, and to the stirring of the knives, which constantly sets in that direction.

To prevent the too rapid advance of the waste toward the outlet M, which would be liable to carry along with it more or less of the valuable ore, and also to thoroughly cut up the bunches of waste and ore and prevent the packing of sand, the spiral line of knives K is set at such an angle to their paths of travel that they will throw the material outwardly and obstruct its travel toward the outlet. In general, they should be set at an angle of about forty-five degrees to their path; but they may be adjusted to any desired angle, and those near the outer ends of the arms may have a greater or lesser angle than those nearer the outlet, thereby insuring the proper rate of advance of the material toward the outlet to obtain the best results.

The shaft S is conveniently rotated by means of a bevel gear-wheel, J, secured to its upper end in engagement with a bevel gear-pinion, G, secured on a horizontal shaft, F, the latter being provided with a band-pulley or gear-wheel, P.

The pan B is provided with a sluice-gate, T, for drawing off the mercury when it is desired to separate the ore therefrom.

Instead of constructing the knives and distributor to rotate, the pan might be made to

rotate and the knives remain stationary, thereby producing a similar effect upon the material treated; but such construction is not deemed the better.

I am aware that stirring-knives have heretofore been secured to rotating arms in spiral form, and that a conical or funnel shaped distributor has been used in connection therewith, and also that stirring-paddles have been set obliquely to their path of travel, and I do not therefore claim such construction, broadly; but,

Having fully described my invention, what I claim as new, and desire to secure by Letters Patent, is—

In an ore-concentrator, a knife-supporting arm radiating from a central operating-shaft, said arm being provided with flanges extending laterally from the same side of the arm, a knife having its stem loosely inserted in the flanges, and a draw-bolt the eye of which embraces the stem of the knife between the flanges, the bolt extending through the body of the arm, whereby the knife is locked to the arm in the desired vertical and angular adjustment, substantially as described.

In testimony whereof I affix my signature in presence of two witnesses.

GEORGE D. STONESTREET.
